UNITED STATES PATENT OFFICE.

CHESTER E. WALKER, OF PEORIA, ILLINOIS.

DEVOTIONAL BENCH.

Application filed September 5, 1921. Serial No. 493,596.

To all whom it may concern:

Be it known that I, CHESTER E. WALKER, a citizen of the United States, a resident of Peoria, in the county of Peoria and State of Illinois, have invented new and useful Improvements in Devotional Benches, of which the following is a specification.

This invention has reference to devotional benches, and it has for its principal object 10 to provide a collapsible or sectional bench, including end supports, a kneeling part and an arm or body rest. The several parts being provided with complementary locking members, whereby the several parts may be 15 easily and quickly assembled and disassembled that the bench may be moved from place to place.

The invention has for a further object to provide a collapsible or sectional bench, including a kneeling part comprising a box in which the several other parts may be stored or housed; the construction of other parts being of such a character that they may have an interfitting relation in said box.

25 That the invention may be more fully understood, reference is had to the accompanying drawings, forming a part of the specification, illustrating a preferred embodiment of the invention, in which:—

30 Fig. 1 is a side elevation of the bench assembled for use;

Fig. 2 is a front elevation of Fig. 1;

Fig. 3 is a front elevation of the bench, disassembled, the parts being in relation to 35 each other ready for assembling;

Fig. 4 is a plan view of the box, the lid being raised to show the other parts of the bench packed or stored therein;

Fig. 5 is a cross section of the box as the 40 same would appear on the line 5—5 Fig. 4;

Fig. 6 is a detail sectional view as the same would appear, if taken on the line 6—6 Fig. 2;

Fig. 7 shows in section the complementary 45 locking members used to connect the arm or body rest, or the box with the supports, and

Fig. 8 is an end elevation of certain of the locking members.

Like characters of reference denote corresponding parts throughout the figures.

The devotional bench herein shown and described may have many uses, but is particularly useful at funeral rites in churches or other places. At certain funeral services 55 it is the custom for friends of the deceased to kneel beside the casket both to view the

deceased person and also to offer prayer for the "repose of the soul" of such deceased person. Heretofore the friends have knelt beside the casket resting the arms and body 60 thereagainst. Such caskets, if finished with highly polished wood or if covered with the light colored cloth, it is at once apparent that the polished surface of the casket not only becomes marred by scratching or the 65 cloth becomes soiled. My bench will obviate this, as well as provide a comfortable kneeling and arm and body rest, and being constructed in knock-down form may be readily and quickly assembled and disassembled and 70 the parts packed for storage in the kneeling box.

The bench includes the end supports 1, 1; the top connecting bar 2 also forming a support or rest for cushions 3, 3, and the kneeling rest 4, preferably made in the form of a box, provided with the hinged lid or cover 5, and also having a handle 6 for moving the box with other parts of the bench packed or stored therein. The lid or cover 5 being 80 upholstered, as at 7, as shown.

The end supports 1, 1, may be of any suitable design, preferably as shown in Fig. 1, but having upper inturned or offset ends 8, preferably faced by the metal strip 9, and 85 said strips and the face of said off-set ends are provided with angular slots 10 forming elements of the complementary locking members for detachably connecting the connecting bar 2 to said supports. The ends of 90 said connecting bar being also faced by the metal strips 11 and having connected thereto or formed thereon the angular hooks 12 which are inserted into the slots 10 and the bar dropped into a position corresponding 95 to that shown in Fig. 7.

The end supports 1 form a compact fit for the bar 2 and the box 6 and the object of the off-set ends 8 is to use a bar 2 shorter than the length of the box 4 so that the former 100 may be stored endwise in the box, when the parts are packed, as shown in Figure 4.

The inner lower faces of the supports 1, 1 are provided with locking elements corresponding to 9 and 10 and the ends of the 105 kneeling rest or box have connected thereto or formed thereon locking elements corresponding to 11 and 12, and adapted to be assembled and disassembled in the manner shown in Fig. 7.

In addition to the securing means described between the ends of the box 4 and the

supports 1, 1, I also provide spring dowel pins 13 in the supports 1, 1, which are adapted to be inserted in openings or slots 14 in the ends of the box, to prevent accidental detachment of the box should the latter be lifted, requiring the pins to be withdrawn before the box may be detached.

The cushions 3, 3, fit end to end on the connecting bar 1, and the latter is provided with 10 openings or slots 15 to receive pins 16 depending from the cushions, see Fig. 6, such connection preventing endwise movement of the cushions and detachably retaining the same in place. I also prefer to make the 15 cushions long enough so that when they are in place on the bar 2 they will extend over the ends of said bar, see Fig. 2.

The cushions 3 are made over, preferably 20 wooden frames 17 which fit snugly over the bar 2, see Fig. 6.

It is obvious from the foregoing description that modifications of structure may be made without departing from the spirit and scope of the invention, and I therefore do 25 not wish to be limited to the structure shown, except as defined by the claims.

What I claim is:

1. A devotional bench, including in combination, a pair of end supports, a bar arranged for detachable connection to the upper ends of said supports, a box having a hinged cover and arranged for detachable connection to the lower ends of said supports, and padded arm rests arranged for detachable connection with said bar, said box 35 adapted to have packed therein the other elements of said bench when disassembled.

2. A devotional bench, including in combination, a pair of spaced end supports, the distance between which at their upper 40 ends is less than at their lower ends, an arm rest spacing and connecting the upper ends of said supports, a kneeling rest spacing and connecting the lower ends of said supports, said kneeling rest comprising a hinged 45 box for housing the arm rest and end supports.

3. A devotional bench, including in combination, a pair of end supports, a kneeling rest spacing and connecting the lower ends 50 of said supports, and comprising a box to receive and store the remaining elements of said bench, an arm rest spacing and connecting the upper ends of said supports, pads for said arm rest, and means for detachably securing said pads to said arm rest.

4. A devotional bench, including in combination, a pair of end supports, a bar to space and connect the upper ends of said 60 supports, said bar and supports having complementary locking means, a box having a hinged cover adapted for spacing and connecting the lower ends of said supports, said box and supports having complementary locking means, and arm rests arranged 65 for removable connection with said bar and to lie lengthwise thereon, said box being of a size suitable to receive the bar, supports and pad for storage and shipping 70 purposes.

In witness whereof I have hereunto affixed my hand this 3rd day of September, 1921.

CHESTER E. WALKER.
